United States Patent Office.

WILLIAM WARD, OF CLEVELAND, OHIO.

Letters Patent No. 82,902, dated October 6, 1868.

IMPROVED METALLIC ROOFING.

The Schedule referred to in these Letters Patent and making part of the same.

TO ALL WHOM IT MAY CONCERN:

Be it known that I, WILLIAM WARD, of Cleveland, in county of Cuyahoga, and State of Ohio, have invented a certain new and Improved Metallic Roofing; and I do hereby declare that the following is a full and complete description of the same, reference being had to the accompanying drawings, making a part of this specification, in which—

Figure 1 represents a section of a roof with the tin sheets partly laid.

Figure 2 is a side view of the same.

Figure 3 is a view of one of the sheets.

Figure 4 is a view of the opposite side of the same.

Like letters of reference refer to like parts in the several views.

The sheets are first cut in the form of an oblong square, indicated by the red line a' , fig. 3. At a short distance from the end a small slit is cut at or about the point D, on each side of the plate; below this the metal is then turned over, forming a flange or lip, A, fig. 3. On the other side the metal is turned in the opposite direction, forming a lip, B; on the opposite side of the sheet, the end of the sheet is then turned up, forming a lip, C, as shown at a' , fig. 4, which is a side view of the sheet. The portion, D, of the plate, at the sides of which there are no flanges, is then bent down, forming a return, as shown at b , fig. 4. These plates are represented by figs. 3 and 4 ready for use.

The manner of applying these plates to the roof is as follows: A strip of metal, E, fig. 1, is secured to the outside edges of the roof projecting over the edges, as shown in fig. 2. Commencing at the corner, the first plate is laid, the lips A and C fitting or lapping over the edges of the metal strip, which leaves the flange B and the piece D' free for the application of the other plates; one or more nails c are then driven through the part D into the roof, as shown at fig. 1. The next plate is then put on the lip or flange A, interlocking with the flange B, and the flange C fitting over the edge of the strip E, the part D being fastened by nails c , and so on, until the first layer of plates is secured to the roof. The next layer is put on in a similar manner, the flange C fitting over the edge d of the part D' , and the flange B interlocking with the flange A, the part D' being secured by nails, which is then covered by the next layer of plates. Thus the nails are completely covered.

What I claim as my improvement, and desire to secure by Letters Patent, is—

The metal roofing, composed of sheets of metal cut and bent, as shown in figs. 3 and 4, having flanges or lips turned thereon, as described, and used with strips D to form the roof, all constructed and arranged in the manner and for the purpose as described.

WILLIAM WARD.
